PORTABLE VEGETABLE PACKING BIN

Benedict F. Reichenberger, Maricopa County,
Ariz.

Application January 29, 1936, Serial No. 61,432

4 Claims. (Cl. 214—1)

My invention relates to improvements in portable bins used for transporting vegetables such as lettuce, cabbage, carrots and other similar crops from the field to a packing shed and thence along 5 a run-way in said shed contiguous to the line of packing operations; and the objects of my improvements are,

First, to provide a bin having slanting sides angularly disposed relative to the bottom so that 10 when the bin is tipped laterally one of the sides will become a trimming or packing bench;

Second, to provide a bin of this class which may be easily attached to, or detached from a wheeled carriage;

Third, to provide a bin of the class described which is adapted to be suspended in a laterally tipped or inclined position on rails to provide free longitudinal movement along the packing line;

Fourth, to provide adjustable means for laterally elevating one side of a bin of the class described;

And fifth, to provide retention of predetermined portions of the pack within said bin, after laterally elevating one side thereof. Other objects will appear hereinafter.

I attain these objectives by the construction devices and mechanism illustrated in the accompanying drawing, in which

Figure 1 is a side elevation thereof, showing 30 the bin in a horizontal position with the position of the longitudinal elevational rail indicated, but not at proportional elevational height, as indicated by break line 46;

Figure 2, an end elevational view, showing the 35 elevating or tipping mechanism and the longitudinal guide rails; the elevated position of the bin as used in packing being indicated by dotted outline.

Similar numerals refer to similar parts in both 40 views.

The bin 2 is provided with a flat bottom 3 and slanting sides 4 and 5 angularly disposed toward the bottom, so that when the bottom is tilted at an angle of approximately 45 degrees from the 45 horizontal, the lower side 4 will be approximately horizontal and the upper side 5 will be approximately vertical. The ends of the bin, 6 and 7, are vertically disposed relative to the bottom. Rollers 8 and 9 are attached, respectively, near 50 the top end corners of side 4. These are positioned and shaped to receive a rounded rail; the axis of the bearing of these rollers being parallel to side 4. Rollers 11 are positioned at the upper corners of side 5. They are shaped and positioned to receive a rounded rail parallel to said

side, and the axes or their bearings are at right angles to said side 5.

The entire bin is supported on under carriage 12, which, in its preferred form, as herewith illustrated, consists of a rectangular frame of channel iron composed of end pieces 13 and 14 and side bars 15. The frame is supported on springs 17, attached to axles 18 which are adjustable as to width, having the rounded end portions, carrying the wheels 19, bolted to the middle channel section 20 by bolts 21. The bin 2 is positioned within this frame so that the bottom 3 extends below this framework, and the weight of the bin is supported by a contact with the sides of the frame. This support is afforded by the open crotch or Y 15 bearings 22 which receive supporting trunnions 23, attached to side 4 and the left hand ends of the bin, and angle braces 24 attached to sides 5 near ends and supported directly on frame rail 15. 20

While the elevating mechanism, herein illustrated, is attached to the carriage 12, it is to be understood that any similarly functioning elevating mechanism may be used, either attached to the carriage or to the line rails 37 and 38 in the shed. The form here illustrated consists of two 25 sheave sectors 25 and 26, journaled on plates attached to approximately the center of end rail 13 and 14 respectively. Each sheave is provided with an arm 16. These carry links 27 connecting to the bosses 28, attached to the bin ends 6 and 30 7, respectively, at points near the top and approximately midway between the center and the right hand edge of the end pieces. Cable 29 extends around sheave 25 and thence to the inner portion of drum 30. A second cable 31 extends from approximately the middle of drum 30, over pulley 32 35 to the left hand of the carriage, as viewed in Fig. 1, thence over pulley 33 to sheave sector 26, which is understood to be the left hand counter-part of the sheave sector 25. The cable drum 30 is operative by means of a worm and sector 34, which may be manipulated by crank 35, attached to shaft 36. 40

As the drum is turned, cables 29 and 31 are wound on drum 30, the sheaves 25 and 26 operating through cranks 16 and rods 27 raise the bin to the position indicated by the dotted outline in Figure 2. As the bin approaches this position the rail 37 receives rollers 8 and 9 thus lifting trunnions 23 out of bearing 22. A swingable rail 38, together with proper supports, is positioned to then receive rollers 11 and support the bin in the elevated position indicated. The direction of swing of this rail is indicated in dotted outline. Rods 27 may then be removed from the bell 55

cranks 16 by the removal of cotter pins 45, and the bin will thus be free to move longitudinally along rails 37 and 38, free from the carriage 12. In order to aline rail 37 with rollers 8 and 9 a 5 channel way 39 is provided at a pre-determined horizontal distance from the center of rail 37.

It is to be understood that the wheels 19 of carriage 12 may be a portion of a truck, or a 10 separate trailer, and may be provided with steering knuckles, or other conventional means for steering, as well as means for attachment to a tractor or other mode of locomotion.

A gate 40, is attached by hinges 41, to the 15 left hand side member 4. This may be held in place vertically as indicated by the dotted lines 42, by pins 43 or swung, either inwardly or outwardly, as desirable. This gate forms a means of retaining the vegetable pack when the bin is full and first tilted to elevated position.

20 In operation, the bin is first placed in the lowered position on the carriage and thus transported to the field where the vegetables are to be harvested. The construction herewith illustrated permits the bin to be built so that its sides do not 25 extend a great distance from the ground. This enables the field cutters to easily throw or otherwise place the vegetables in the bin. After thus loading, the bin is transported on the carriage 12, to the packing shed, where it is raised by the 30 elevating mechanism above described with one side (the right as illustrated in Fig. 2) so that the left hand side, 4, becomes a bench or table, from which trimmers or packers may remove the vegetables. In case the load is heavy and the 35 pack of vegetables is inclined to roll easily, retaining gate 40 may be fixed in the position indicated by the dotted lines 42, before the bin is elevated. After being placed on the rails 37 and 38, the bin may be moved longitudinally to any 40 desired position along the packing line. The carriage 12, being removed and no longer necessary as a support for the bin, may be used to transport an empty bin of similar proportions and construction back to the field, thus several 45 bins may be used with one carriage.

Since the bin is in the tilted position above described the vegetables slide down upon the lower side 4, which forms a bench or working table. As fast as the vegetables on this bench are removed 50 others fill their place due to the slant of the bottom of the bin. Thus, all vegetables contained in the bin become within easy reach of the trimmers or packers. The position of gate 40 and the degree of slant regulate the flow of the pack, it 55 being understood that some vegetables and fruits must be handled more gently and slowly than others.

It is to be understood that the use of rails 37 and 38 is optional. The bin is completely operative by the use of the carriage 12 and its depending mechanism alone. Thus in sheds not provided with line rails the bin is not removed from the carriage but—in case this is in the form of

a trailer—it is merely un-hooked from the truck or tractor used to draw it, the bin elevated to the desired slant, and then rolled along the packing line on the wheels of the carriage.

From the foregoing it is obvious that I have 5 provided a means for harvesting fruits and vegetables, of the class described, which will eliminate the use of field packing crates and the necessary double handling due to the use of these 10 crates.

Having now explained the construction of my bin and its operation, I desire to claim as new and novel the following:

I claim,—

1. A portable vegetable packing bin having a 15 bottom substantially rectangular in shape with sides slanting outward toward the top, and ends vertically disposed relative to said bottom, a gate hingedly mounted on one of said sides, means for positioning said gate at a pre-determined angle 20 relative to said side, rollers affixed to said sides adapted to receive rails and positioned so that said bin may be moved longitudinally while in a tilted position, and means for removably attaching said bin to a wheeled carriage. 25

2. A portable vegetable packing bin comprising a bin-body having a substantially rectangular shape with sides outwardly extending from the bottom, means for removably attaching said bin to a wheeled carriage, said means including trunnions affixed to one side of said bin and angle braces disposed on the opposite side thereto, in combination with a supporting carriage with wheels positioned to provide longitudinal movement, and means for receiving and supporting 30 said bin including bearings adapted to receive the trunnions on said bin, and a frame piece adapted to receive said angle braces, and means for elevating one side of said bin while on said carriage whereby it is supported at a slant so 35 that the lower side may be used as a packing bench, said means including sheave sectors, at each end of said carriage, coincidentally operated by power increasing mechanism to secure 40 mechanical advantage, connected by bell cranks 45 and links to the sides of said bin, opposite said trunnion bearings.

3. A portable vegetable packing bin having outwardly slanting sides, rollers affixed to said sides adapted to receive rails and positioned so 50 that said bin may be moved longitudinally while in a tilted position, and means for removably attaching said bin to a wheeled carriage. 55

4. A portable vegetable packing bin having a bottom substantially rectangular in shape with 55 ends vertically disposed relative thereto and sides extending therefrom at an angle greater than ninety degrees, rollers affixed to said sides adapted to receive rails whereby said bin may be moved longitudinally thereon and means for removably 60 attaching said bin to a wheeled carriage.

BENEDICT F. REICHENBERGER.
